United States Patent Office

Des. 185,203
Patented May 19, 1959

185,203

ARTICLE CARRYING CART

Walter Hollinger, Chicago, Ill.

Application August 27, 1957, Serial No. 47,520

Term of patent 3½ years

(Cl. D14—3)

Fig. 1

Fig. 2

Fig. 3

Fig. 1 is a perspective view of an article carrying cart, showing my new design;

Fig. 2 is a top plan view thereof;

Fig. 3 is a rear elevational view thereof.

I claim:

The ornamental design for an article carrying cart, as shown.
